ABSTRACT

A lighter employing electric spark ignition includes a casing and a gas reservoir defining therebetween a space in which is mounted a movable supporting plate carrying on one side thereof an electric cell, a voltage-raising circuit, a switch for connecting the cell to the voltage-raising circuit, and an ignition electrode. The other side of the supporting plate has a printed circuit establishing electrical connections between the components on the one side of the plate. A gas outlet valve is operatively engaged by the supporting plate and controls the supply of gas from the reservoir to a burner adjacent which the ignition electrode is disposed. A control member is operable to close the switch and displace the supporting plate to open the gas outlet valve, with the switch being closed before opening of the valve. In one form of the invention, the supporting plate forms a lever having one end engaged with the gas outlet valve and the switch at its other end. In another form of the invention the supporting plate has a first extension engaged with the gas outlet valve and a second extension connected to the control member which imparts a translational movement to the supporting plate.

LIGHTER EMPLOYING ELECTRIC SPARK IGNITION

This invention relates to a lighter employing electric spark ignition and comprising a holder for receiving an electric cell, a voltage-raising circuit, a switch which is closable in response to operation of a control member to connect the voltage-raising circuit electrically to the electric cell received in the holder in use, and an ignition electrode disposed adjacent a burner and electrically connected to the voltage-raising circuit, operation of the control member resulting in opening of a gas outlet valve feeding the burner.

Lighters of the above kind may be constructed as disclosed in the Applicants' French Pat. No. 72 02407 of 25th Jan. 1972 and its three Certificates of Addition No. 72 12833 of 12th Apr. 1972, No. 72 24714 of 7th July 1972 and No. 72 43967 of 11th Dec. 1972. Hitherto, in such lighters, the cell holder, the voltage-raising circuit, the ignition electrode, the switch and the control member were variously arranged and occupied a relatively large volume in relation to the total volume of the lighter.

According to the present invention, there is provided a lighter employing electric spark ignition and comprising a holder for receiving an electric cell, a voltage-raising circuit, a switch which is closable in response to operation of a control member to connect the voltage-raising circuit electrically to the electric cell received in the holder in use, and an ignition electrode disposed adjacent a burner and electrically connected to the voltage-raising circuit, in which lighter the cell holder, the voltage-raising circuit, the switch and the ignition electrode are disposed on a supporting plate having a portion operatively engaged with a gas outlet valve feeding the burner, the supporting plate being movably mounted between two fixed structures of the lighter, and the control member being operable to close the switch and move the supporting plate to open the gas outlet valve.

Preferably, the supporting plate is mounted between a reservoir and a casing of the lighter.

The switch may be directly actuated by the control member and, in one such embodiment, the supporting plate forms a lever which is fulcrumed intermediate its ends on one of the said two fixed structures of the lighter, one end of the lever being operatively engaged with the gas outlet valve, and the other end of the lever being movable by the control member via the switch. In this embodiment the switch has a movable contact including a resilient member which is resiliently deformable by the control member to close the switch.

Closure of the switch may result from the movement of the supporting plate in response to operation of the control member and, in one such embodiment, the supporting plate forms a lever having one end operatively engaged with the gas outlet valve and the other end engagable with one of the said fixed structures of the lighter via the switch, the control member being operable to act on the lever intermediate the ends of the lever to move the said other end of the lever into engagement with the said one fixed structure to close the switch. In this embodiment the switch has a movable contact including a resilient member which is resiliently deformable by abutment with said one fixed structure to close the switch.

In another embodiment where closure of the switch results from movement of the supporting plate, the plate is arranged to undergo a translational movement in response to operation of the control member, one side of the supporting plate presenting a first bifurcated lateral extension operatively engaged with the gas outlet valve, and the other side of the supporting plate presenting a second lateral extension connected to the control member. In this embodiment, the switch has a movable contact including a resilient member which is resiliently deformable to close the switch by abutment with one of the said fixed structures of the lighter in response to movement of the supporting plate by operation of the control member.

Embodiments of the invention provide a space-saving arrangement of the cell holder, the voltage-raising circuit, the ignition electrode and the control member and minimise the number and length of the electrical connections. Further, automatic manufacture of the part of the lighter concerned with its electric ignition is enabled

In order that the invention may be readily understood, embodiments thereof will now be described in more detail, by way of example, with reference to the accompanying drawings, in which:

FIG. 1 is a sectional view of a lighter according to a first embodiment of the invention;

FIG. 2 is a sectional view illustrating a modified detail of the lighter illustrated in FIG. 1;

FIG. 3 is a sectional view of a lighter according to a second embodiment of the invention; and

FIG. 4 is a sectional view of a lighter according to a third embodiment of the invention.

FIGS. 1 and 2 show a gas lighter employing electric spark ignition and comprising a reservoir 1 for liquefied gas and a casing 2. The reservoir 1 has a filling valve 3 and an outlet device 4 which as a rule is so constructed that it can vary the gas output so as to control the height of the flame. The outlet device 4 comprises a gas outlet valve 5 feeding a burner 6, the gas outlet valve 5 opening against the force of a spring 7 which normally keeps it closed.

For the purpose of electric spark ignition, the lighter has an electrical cell 8, a voltage-raising circuit 9, an ignition electrode 10 electrically connected to circuit 9, a switch 11 and a control member 12 operable by the user to close the switch 11 electrically to connect cell 8 to circuit 9 and to open the gas outlet valve 5 feeding the burner 6 adjacent which the ignition electrode 12 is disposed. When the user operates the control member 12, a spark is delivered at the electrode 12 to ignite the gas fed to the burner 6.

The cell 8, the voltage-raising circuit 9, the ignition electrode 10 and the switch 11 are disposed on a supporting plate 13 one portion 13a of which operatively engages the gas outlet valve 5, the supporting plate 13 being freely mounted between two fixed structures of the lighter, i.e., between its reservoir 1 and its casing 2. Towards its end 13a the supporting plate 13 takes the form of a fork engaging around the gas outlet valve 5 below the burner 6, so that it can open the gas outlet valve 5 against the force of the spring 7.

The control member 12 of the lighter is adapted to displace the supporting plate 13 and to cause the closure of the switch 11 and the opening of the gas outlet valve 5. Operation of the control member 12 first causes the closure of the switch 11 and then the open-

ing of the gas outlet valve 5, the offset between the closure of the switch 11 and the opening of the gas outlet valve 5 corresponding to the time needed to produce the spark in the voltage-raising circuit 9.

The supporting plate 13 is made of an insulating material, the cell 8, the voltage-raising circuit 9, the ignition electrode 10 and the switch 11 being disposed on one side of the supporting plate 13. On the other side of the supporting plate 13 there is disposed a printed circuit 14 providing the electrical connections between the cell 8, the voltage-raising circuit 9, the ignition electrode 10 and the switch 11.

The cell 8 is retained by a holder in the form of a claw clip 15 attached to the supporting plate by pins 16 extending through the supporting plate to the printed circuit 14 to which they are electrically connected. The pins 16 thus fix the clip 15 to the supporting plate 13 and electrically connect a first pole of the cell 8 to the printed circuit 14.

Disposed beside the clip 15 is a movable switch contact in the form of a resilient strip-shaped member 17 extending above the cell 8 and attached to the supporting plate 13 by pins 18 extending through the supporting plate to the printed circuit 14. The pins 18 fix the resilient member 17 to the supporting plate 13 and electrically connect the resilient member 17 to the printed circuit 14. The switch 11 is therefore formed by the resilient member 17 and the second pole of the cell 8.

The voltage-raising circuit 9 includes an integrated circuit 19 which supports an inductance coil 20 and is attached to the supporting plate 13 by pins 21 extending through the supporting plate to the printed circuit 14. The pins 21 fix the integrated circuit 19 to the supporting plate 13 and electrically connect the integrated circuit 19 to the printed circuit 14. The voltage-raising circuit 9 also includes a capacitor 22 which is attached to the supporting plate 13 by a pin 23 extending through the supporting plate to the printed circuit 14. The pin 23 fixes the capacitor 22 to the supporting plate 13 and electrically connects the capacitor 22 to the printed circuit 14. The voltage-raising circuit 9 further includes a transformer 24 having a primary winding 24a and a secondary winding 24b wound on an insulating ferrite core 24c which is attached to the supporting plate 13 by two pins 25 extending through the supporting plate to the printed circuit 14. The pins 25 fix the ferrite core 24c to the supporting plate 13 and electrically connect the primary winding 24a and the secondary winding 24b to the printed circuit 14.

A single ignition electrode 10 is attached to the ferrite core 24c and is electrically connected to the secondary winding 24b. Preferably the ferrite core 24c comprises a portion of minor diameter around which the secondary winding 24b is wound, the primary winding 24a being wound around the secondary winding 24b. As a support for the ignition electrode 10, the ferrite core 24c has a portion of major diameter (a diameter at least equal to the diameter of the primary winding 24a), such portion of major diameter forming a thermal screen between the burner 6 and the primary and secondary windings 24a and 24b. This portion of major diameter bears the pins 25. The ignition spark is struck between the ignition electrode 10 and the burner 6 which is in the form of a diffuser burner having a central aperture 6a enclosed by an annular aperture 6b.

The burner 6 is electrically connected to the printed circuit 14 via a contact member 26 interposed between the supporting plate 13 and the burner 6 and attached to the supporting plate 13 via a pin 27 extending through the supporting plate to the printed circuit 14. The pin 27 fixes the contact member 26 to the supporting plate 13 and electrically connects it to the printed circuit 14.

In the embodiment of the invention illustrated in FIG. 1 the supporting plate 13 is constructed to form a lever whose forked end 13a cooperates with the gas outlet valve 5. A central region 13c of the plate 13 bears on a fulcrum in the form of a transverse boss 1a provided on the reservoir 1. The other end 13b of the plate 13 is movable by the control member 12 via the switch 11. To this end the fixed terminal of the switch 11 is formed by the second pole of the cell 8 mounted on the supporting plate 13, the movable switch terminal being formed by the resilient member 17 which cooperates with the control member 12.

As shown in FIG. 1, the control member 12 is adapted to be pushed in the direction indicated by the arrow F to cause flexion in the resilient member 17, so that initially the resilient member 17 contacts the terminal of the cell 8 to close the switch 11 and then the resilient member 17 transmits the descending movement of the control member 12 to the supporting plate 13 to cause the plate 13 to pivot and the gas outlet valve 5 to rise and open.

FIG. 2 shows a modification of the FIG. 1 embodiment, in which the control member 12 is slidable in the direction of the arrow G. In this case the control member 12 comprises a ramp 12a to cause closure of the switch 11 and the pivoting of the supporting plate 13 to lift the gas outlet valves.

In the embodiment of the invention illustrated in FIG. 3 (in which like members to those shown in FIG. 1 have like references), the supporting plate 13 is constructed to form a lever whose forked end 13a cooperates with the gas outlet valve 5. The other end 13b of the plate 13 is arranged for engagement with a projection 2a on the casing 2 via the switch 11, when the plate 13 is displaced upwardly by the control member 12 which acts on a central zone 13d of the plate 13. To this end, one of the terminals of the switch 11 is formed by a terminal of the cell 8 the other terminal being formed by the resilient member 17 which is brought into engagement with the projection 2a.

The control member 12 is adapted to be pushed in the direction indicated by the arrow H to cause the pivoting of the supporting plate 13 around its end 13a, so that initially the resilient member 17 abuts the projection 2a and comes into contact with the terminal of the cell 8 to close the switch 11 and then the supporting plate 13 pivots around its end 13b to make the gas outlet valve 5 rise and open, the spring 7 of the gas outlet valve 5 having much more rigid elasticity characteristics than those of the resilient member 17.

In the embodiment of the invention illustrated in FIG. 4 (in which like members to those shown in FIG. 1 have like references) the supporting plate 13 is constructed to be displaced by a translational movement. The supporting plate 13 therefore comprises, on the side bearing the printed circuit 14, a first bifurcated lateral extension 13e operatively engaging the gas outlet valve 5, and, on the side remote from the printed circuit 14, a second lateral extension 13f connected to the

control member 12. The first lateral extension 13e is made at least partly of an electrically conductive material and is connected to the printed circuit 14.

One of the terminals of the switch 11 is formed by a terminal of the cell 8 connected to the supporting plate 13, the other terminal being formed by the resilient member 17 which can abut a projection 2b on the casting 2.

The control member 12 is slidable in the direction shown by the arrow J to cause the traversing of the supporting plate 13, so that the resilient member 17 first abuts the projection 2b and comes into contact with the terminal of the cell 8 to close the switch 11, and then the first lateral extension 13e of the supporting plate 13 causes the raising and opening of the gas outlet valve 5. The spring of the gas outlet valve 5 constitutes resilient return means returning the supporting plate 13 into its initial position after the actuation of the control member 12.

In the lighter of FIG. 4 the expansion device 4 is mounted just below the gas outlet valve 5 and serves to vary the gas output in order to adjust the height of the flame. A knurled disc 4a is provided for this purpose.

The transformer 24 of the voltage-raising circuit 9 of FIG. 4 comprises a portion of minor diameter around which the secondary and primary windings are wound and a portion of major diameter attached by its base to the supporting plate 13. The ignition electrode 10 is attached to the portion of major diameter and extends through the supporting plate 13.

Whichever of the above embodiments is adopted, the normal actuation of the control member 12 by the user of the lighter first causes the closure of the switch 11 and then the opening of the gas outlet valve 5. The offset between the closure of the switch 11 and the opening of the gas outlet valve 5 is about 0.3 s, corresponding to the time required to produce the spark in the voltage-raising circuit. Any loss of gas due to premature opening of the gas outlet valve 5 is therefore obviated.

Finally, the lighters embodying the invention have a certain number of advantages which can be summarised as follows.

The lighter is made up of three simple elements namely the lighter reservoir, its casing and the supporting plate bearing that portion of the lighter which is used for its electric ignition and acting as a fork for opening the gas outlet valve. These elements are readily interchangeable without any need for a specialized technician.

In view of the simplicity of operation of the lighter, it is much more reliable than has been possible with conventional electrically ignited lighters. The cell can readily be replaced simply by disengagement and engagement in its claw clip. Parasitic contacts, which always cause malfunctioning, are limited to the minimum.

From the manufacturing aspect, it is extremely simple to assemble the electric or electronic components on the supporting plate.

The construction of the transformer and its insulating ferrite core enables such core to be used as a thermal screen and as a support for the ignition electrode.

Lastly, the lighter can be constructed with a rechargeable reservoir or a throw-away one. In the former case there is no particular problem in periodically

replacing the reservoir, *inter alia* if the expansion device becomes worn.

We claim:

1. A lighter employing electric spark ignition, which lighter comprises:

a body including a reservoir for gas, said body having two fixed structures defining a space therebetween;

a burner supported within said body;

a gas outlet valve arranged between said burner and the reservoir of said body for controlling the supply of gas from the reservoir to said burner;

a supporting plate movably mounted in the space between said two fixed structures of said body and having a portion operatively engaged with said gas outlet valve for opening said valve on movement of said supporting plate;

an electric cell disposed on said supporting plate; a voltage-raising circuit disposed on said supporting plate;

a switch disposed on said supporting plate for electrically connecting said electric cell to said voltage-raising circuit;

an ignition electrode disposed on said supporting plate and adjacent said burner; and

a control member supported by said body and operable to move said supporting plate and close said switch.

2. A lighter as claimed in claim 1, wherein operation of said control member first closes said switch and then opens said gas outlet valve.

3. A lighter as claimed in claim 1, wherein one of said two fixed structures of said body comprises a fulcrum, and said supporting plate is supported intermediate its ends on said fulcrum to form a lever one end of which is operatively engaged with said gas outlet valve and the other end of which is movable by said control member via said switch.

4. A lighter as claimed in claim 3, wherein said switch has a movable contact, said movable contact including a resilient member which is resiliently deformable by said control member to close said switch.

5. A lighter as claimed in claim 1, wherein closure of said switch results from the movement of said supporting plate in response to operation of said control member.

6. A lighter as claimed in claim 5, wherein one of said two fixed structures of said body comprises an abutment and said supporting plate forms a lever having one end operatively engaged with said gas outlet valve and the other end engageable with said abutment, said control member being operable to act on the lever intermediate the ends of the lever to move the said other end of the lever into engagement with said abutment to close the switch.

7. A lighter as claimed in claim 6, wherein said switch has a movable contact, said movable contact including a resilient member which is resiliently deformable by engagement with said abutment to close said switch.

8. A lighter as claimed in claim 1, wherein said supporting plate is mounted for translational movement in response to operation of said control member.

9. A lighter as claimed in claim 8, wherein said supporting plate presents on one side thereof a first bifurcated lateral extension operatively engaged with said gas outlet valve, and said supporting plate presents on

the other side thereof a second lateral extension connected to said control member.

10. A lighter as claimed in claim 8, wherein one of said two fixed structures of said body comprises an abutment and said switch has a movable contact, said movable contact including a resilient member which is resiliently deformable to close said switch by engagement with said abutment in response to movement of the supporting plate by operation of said control member.

11. A lighter as claimed in claim 1, including a holder for said electric cell, said holder comprising a clip attached to said supporting plate and having claws for resiliently engaging and retaining said cell.

12. A lighter as claimed in claim 11, wherein said switch comprises a movable contact, said movable contact comprising a resilient strip attached to said supporting plate and extending in spaced relation to said holder, closure of said switch being effected by resilient deformation of said strip into contact with a pole of said cell.

13. A lighter as claimed in claim 1, wherein said voltage-raising circuit comprises an integrated circuit, a capacitor and a transformer each attached to said supporting plate, said integrated circuit supporting an inductance coil.

14. A lighter as claimed in claim 13, wherein said transformer comprises an insulating ferrite core and primary and secondary windings wound on said core, said core having a portion of minor diameter receiving

30

said windings and a portion of major diameter forming a thermal screen.

15. A lighter as claimed in claim 14, wherein said ferrite core portion of major diameter bears said ignition electrode and comprises means for attachment of said transformer to said supporting plate.

16. A lighter as claimed in claim 1, wherein said supporting plate is made of electrically insulating material, said supporting plate having disposed on one side thereof said cell, said voltage-raising circuit, said ignition electrode and said switch, and having on the other side thereof a printed circuit providing electrical connections between said holder, said voltage-raising circuit, said ignition electrode and said switch.

17. A lighter as claimed in claim 16, including a contact member attached to said supporting plate, said contact member being interposed between said supporting plate and said burner to connect said burner electrically to said printed circuit for generation of an ignition spark between said ignition electrode and said burner upon closure of said switch.

18. A lighter as claimed in claim 16, wherein all the elements attached to said supporting plate comprise pins fixing such elements to the supporting plate and electrically connecting the elements to the printed circuit.

19. A lighter according to claim 1, including a casing, said supporting plate being mounted between said reservoir and said casing.
